UNITED STATES PATENT OFFICE

109,681

DESIGN FOR A DRESS

Dorothy Beilinson, New York, N. Y.

Application April 15, 1938, Serial No. 76,507

Term of patent 3½ years

To all whom it may concern:

Be it known that I, Dorothy Beilinson, a citizen of the United States and a resident of the city of New York, in the county of Kings and State of New York, whose post office address is 170 Jaffrey Street, Brooklyn, New York, have invented a new, original, and ornamental Design for a Dress, of which the following is a specification, reference being had to the accompanying drawing, constituting a part thereof,

Fig. 1 is a front view of the dress.

Fig. 2 is the rear view of the dress showing my new design as shown in Fig. 1.

I claim:

The ornamental design for a dress substantially as shown.

DOROTHY BEILINSON.
